UNITED STATES PATENT OFFICE.

MICHAEL WILLIAM COSTELLO, OF BOSTON, MASSACHUSETTS.

VENTILATING CHIMNEY-COWL.

SPECIFICATION forming part of Letters Patent No. 339,863, dated April 13, 1886.

Application filed March 1, 1886. Serial No. 193,599. (No model.)

To all whom it may concern:

Be it known that I, MICHAEL WILLIAM COSTELLO, of Boston, in the county of Suffolk, of the Commonwealth of Massachusetts, have invented a new and useful Improvement 5 in Chimney or Flue Cowl or Ventilators; and I do hereby declare the same to be described in the following specification and represented in the accompanying drawings, of which—

Figure 1 is a side elevation, Fig. 2 a front view, and Fig. 3 a vertical and longitudinal section, of a cowl or ventilator containing my invention, the nature of which is defined in the claim hereinafter presented.

The rotary head A of this cowl or ventilator is composed not only of a hollow cone, a, but of a tubular neck, b, extending down from and opening into the cone in manner as represented. This neck swivels or turns around 15 upon and opens into a flue or pipe, B, provided with a spindle, c, fastened to and extended up from bars d and e, and through a bar, f, and into a socket or step, g. The two bars d and e go diametrically across the flue 20 or pipe B at right angles to one another. The bar f in like manner extends across the neck b, the step being at the top or upper part of the hood or cone a. A vane, C, is fixed lengthwise upon and projects above the said cone a 25 in the manner as shown.

A rotary chimney-cowl substantially so constructed is an old device to which my improvement has reference, which consists in such a cowl having in the upper part of its 30 hollow cone a series of triangular openings, d', and to each of them, and extending within the cone, an air-duct, e', the whole being so that when air is blowing in a direction of the axis and toward the nose of the cone such air 35 will enter and pass through the several ducts and into and through the cone, the currents of such air in passing into and out of the cone serving not only to induce a current of air or smoke upward into the cone, but to 40 force or drive such air or smoke out of the mouth of the cone.

I am aware that it is not new to provide a chimney-cowl of this description with a pipe or duct opening through the nose or front 45 end of the hood and arranged at the middle

of such end, and therefore I do not claim the same. Such an arrangement of an air-induct, besides causing the said induct to be an impediment to the passage of the smoke or air upward into and through the hood, is disadvantageous in other respects, it being liable 55 to produce at times in the flue a downdraft of the smoke or air; also, to operate to prevent the wind from revolving the cowl-head. By having the series of ducts arranged in the upper part of the cone, generally above its axis, and mostly, if not entirely, opening their rear ends in advance of the spindle of the cowl, as represented, the smoke in passing upward into and through the hood is not materially impeded by such ducts, but is met 60 by the air-currents escaping through them, and is by them forcibly driven out of the cowl, the ascending current of smoke or foul-air in the flue or chimney being at the time increased in velocity.

I am aware of the ventilators shown and described in the United States Patents Nos. 76,859, 181,050, 239,418, and 261,404. In two of such patents are revoluble cowls represented, neither of which has any air-ducts in its upper part. In the remaining two of such patents the ventilators are upright ones and not revoluble, they having openings or ducts in their sides. I make no claim there- 75 to, my improvement having reference to a revoluble cowl, and consisting in a specific arrangement of air-ducts therein—viz., in the upper half of the hood, without there being any in its lower half.

With my arrangement and form of hood the air blows against the hood endwise of it and in a direction to cause it to pass directly through each air-induct without first striking against the hood at a right angle or there- 85 about to the axis of the opening, and next being deflected upward through such opening. Besides, having no inducts in the part of the hood that is below its axis, the smoke can escape with less obstruction from the 90 hood, comparatively speaking. The inducts, as arranged, operate with the air when passing through them to keep the hood steady in the general direction of the air and prevent it from being too suddenly or quickly 100

vibrated by aerial currents striking its vane laterally of it.

I claim—

The combination, with the rotary conical 5 hood of a flue-ventilator or chimney-cowl, as described, of a series of air-inducts arranged in the upper half of such hood only, and

opening out of it laterally, and open at their front and rear ends, all being substantially as represented.

MICHAEL WILLIAM COSTELLO.
